UNITED STATES PATENT OFFICE.

WILLIAM H. BROWNELL, OF BROOKLYN, NEW YORK.

DESIGN FOR A PLAQUE.

SPECIFICATION forming part of Design No. 15,881, dated March 3, 1885.

Application filed January 10, 1885. Term of patent 7 years.

To all whom it may concern:

Be it known that I, WILLIAM H. BROWNELL, of Brooklyn, in the county of Kings and State of New York, have invented and produced a new and original Design for Plaques, of which the following is a full, clear, and exact description.

Reference is to be had to the accompanying drawings, forming part of this specification, in which similar letters of reference indicate corresponding parts in both the figures.

Figure 1 is a face view of my new design for plaques. Fig. 2 is a cross-sectional view of part of the same.

15 A is a concave plaque. B is a flat border; C, an ogee molding extending from the edge

of the plaque to the inner edge of the border; D, a concave quadrant molding on the outer edge of the border; E, a straight part on the lower edge of the molding D; F, an external 20 bead on the free edge of the part E.

I claim—

The herein-described design for plaques, consisting of a circular plaque having a flat border, on the outer edge of which a concaved 25 quadrant molding, D, a straight part, E, and an external bead, F, are formed, substantially as herein shown and described.

WILLIAM H. BROWNELL.
